G. H. GILMAN.
FEED CONTROLLING DEVICE.
APPLICATION FILED DEC. 10, 1917.

1,362,990.

Patented Dec. 21, 1920.

UNITED STATES PATENT OFFICE.

GEORGE H. GILMAN, OF CLAREMONT, NEW HAMPSHIRE, ASSIGNOR TO SULLIVAN MACHINERY COMPANY, A CORPORATION OF MASSACHUSETTS.

FEED-CONTROLLING DEVICE.

1,362,990.

Specification of Letters Patent. Patented Dec. 21, 1920.

Application filed December 10, 1917. Serial No. 206,468.

To all whom it may concern:

Be it known that I, GEORGE H. GILMAN, a citizen of the United States, residing at Claremont, in the county of Sullivan and State of New Hampshire, have invented certain new and useful Improvements in Feed-Controlling Devices, of which the following is a full, clear, and exact specification.

10 My invention relates to feed controlling devices.

In my previous Patent, No. 1,151,261, I have described and claimed an improved feeding means especially adapted to use in connection with percussive tools, wherein a braking or retarding device in the form of a resilient member is provided to act upon one of the feeding elements. My present invention has for its object to provide an improved feeding device of the type set forth, wherein, through an improved combination including intermediate connections between the resilient member and the feeding element, the feeding operation is rendered more smooth and any difficulty arising from occasional sticking of the same is entirely overcome.

In the accompanying drawings, I have shown for purposes of illustration one embodiment which my invention may assume in practice.

In these drawings,—

Figure 1 is a side elevation of a feeding mechanism equipped with my improvement, the feed cylinder and retarding mechanism being shown in section to facilitate illustration.

Fig. 2 is an enlarged longitudinal sectional view of the retarding mechanism in position relative to the feeding element.

Fig. 3 is a transverse sectional view, with parts broken away, showing the controlling or retarding mechanism.

Fig. 4 is a detail perspective view, partially broken away, of the braking means *per se* and its housing.

Fig. 5 is an end elevation of the construction shown in Fig. 4.

Fig. 6 is a side elevation of the same.

While a feeding mechanism of either the moving cylinder or moving piston type may be employed, in this illustrative construction I have shown a feeding mechanism including a feed cylinder 1 adapted to be clamped by any suitable clamp 2 to a support 3 and having therein a moving feed piston 4 provided with a piston rod 5. This rod 5, as shown, has swiveled on its outer end a swinging support or bracket 6 which in turn supports a percussive tool 7, herein shown in the form of a hammer drill. In this construction, as in a usual construction, changes in the position of the piston 4 in the cylinder, and therefore in the position of this tool 7, are produced by fluid pressure through the manipulation of a suitable tool and feed controlling valve 8, herein located on the support 6 and controlling the supply of air from any suitable source through passage-ways 9 and 10 leading through the rod 5 to the opposite sides of the piston 4. As in my previous construction, it will also be observed that upon the front head 11 of the cylinder 1, I have provided a braking or feed restraining means including a rotatable worm 12, a worm gear 13 engaged by said worm and disposed concentrically with the piston rod, and a coiled member 15 constituting an elastic feed restraining or brake applying member. Said brake applying member is in the form of a coiled spring surrounding the piston rod, and one end 14 of said member 15 is engaged with and slidably longitudinally in a slot in the worm gear 13, while the other end 16 is attached to the head 11.

In my improved construction, it will be observed that disposed between the spring 15 and the piston rod 5 and around the latter, is a brake lining 17. In a preferred form, this lining is made of a well known fiber composition adapted to exert a powerful braking effect and yet to withstand wear. As shown, this brake lining is divided into coöperating portions, herein shown in the form of halves, disposed on opposite sides of the rod 5 and carried in a resilient two-part metallic housing or casing

18, 19, the lining being inset in a suitable internal groove 20 in the inner periphery of each part and disposed substantially flush with the inner periphery thereof. The two 5 parts 18 and 19 of this housing are, in turn, preferably so disposed as to leave a longitudinally disposed gap extending between the adjacent edges of each part, and each of the same is also preferably provided with a series 10 of longitudinally disposed slots 21 oppositely disposed or staggered and each extending substantially throughout the length of the housing in such a manner as to produce a readily compressible casing which at 15 the same time is highly resilient.

In the operation of my improved construction, the tool 7 will obviously move with the piston rod 5 in accordance with the variations in the supply of pressure fluid 20 brought about by adjustment of the member 8. The movement of the piston rod 5 will, moreover, also be controlled, as in my previous construction, by manipulation of the member 12. In my improved construction, 25 however, it will be observed that the rotation of this member and its connected worm and worm gear does not cause the spring 15 to act directly upon the piston rod, the same instead acting through the live or active intermediate braking member. More specifically, it will be observed that the movement 30 of these members toward braking position causes the spring to be contracted about the two-part member 18, 19 in such a manner as to contract the latter and thus cause the brake lining 17 to engage the surface of the piston rod 5. Obviously, due to the construction of the members 18 and 19, it will also be observed that the resiliency of these 35 members will assist in producing a relatively even application of the retarding effect upon the surface of the rod 5. Further, when the controlling members are released, these members 18 and 19 will also then act 40 gradually and surely to release the piston member 5, the same again returning to their normal configurations and carrying the brake lining 17 with them. In fact, it has been found that whatever the operation 45 of the controlling mechanism 12, 13, 15, through the utilization of my improved live braking unit not only is the retarding influence rendered entirely even, but the release of the parts is also of such a character 50 as to avoid any tendency whatsoever toward jamming of the feed as has occasionally occurred heretofore under certain conditions.

As a result of my improvement, it will 55 also be observed that a construction is produced which, while greatly improving the operation of the device under certain conditions, may nevertheless be manufactured at small expense and applied to existing devices without extensive redesign. It will also 60 be noted that due to the provision of my im-

proved elements 18 and 19, and their brake lining 17, a construction is produced having greatly increased wearing qualities, practically the entire wear being taken upon the brake lining, which is readily replaceable, 70 or upon the surfaces of the members 18 and 19, which are likewise readily replaceable when desired, although the wear on these elements is so small as to render replacements ordinarily unnecessary. These and 75 other advantages of my improved construction will, however, be clearly apparent to those skilled in the art.

While I have in this application specifically described one embodiment which my 80 invention may assume in practice, it will be understood that this form of the same is used for illustrative purposes only and that the invention may be modified and embodied in various other forms without departing 85 from its spirit or the scope of the appended claims.

What I claim as new and desire to secure by Letters Patent is:

1. In combination with a feeding mechanism having a longitudinally movable member, a controlling mechanism comprising an elastic feed restraining member surrounding said first mentioned member, and an active braking member freely disposed between said restraining member and said longitudinally movable member. 90

2. In combination with a feeding mechanism having a longitudinally movable member, a controlling mechanism including an elastic feed restraining member surrounding said longitudinally movable member, and a resilient braking member disposed between said restraining member and said longitudinally movable member. 100

3. In combination with a feeding mechanism having a longitudinally movable member, a controlling mechanism including an elastic feed restraining member surrounding said longitudinally movable member, and an 110 expandible and contractible braking member disposed between said restraining member and said longitudinally movable member.

4. In combination with a feeding mechanism having a longitudinally movable member, controlling mechanism including an elastic feed restraining member surrounding said longitudinally movable member, and a plural-part resilient braking member disposed between said restraining member and 120 said longitudinally movable member.

5. In combination with a feeding mechanism having a longitudinally movable member, a controlling mechanism including an elastic feed restraining member surrounding 125 said longitudinally movable member, a brake lining disposed between the same and a part of said feeding mechanism, and a container housing said brake lining.

6. In combination with a feeding mecha-

- nism having a longitudinally movable member, a controlling mechanism comprising a relatively stationary elastic feed restraining member surrounding said first mentioned member and spaced therefrom, and a separate brake member disposed in said space.
7. In combination with a feeding mechanism having a longitudinally movable member, a controlling mechanism comprising a relatively stationary elastic feed restraining member surrounding said first mentioned member and spaced therefrom, and a brake member disposed in said space and unconnected with said other members.
8. In combination with a feeding mechanism having a longitudinally movable member, a controlling mechanism comprising an elastic member surrounding said longitudinally movable member and spaced therefrom by a relatively annular space, a brake member normally loosely occupying said space, and means for placing said elastic member under constraint to reduce said space and compress said brake member closely around said first mentioned member.
9. In an apparatus of the character described, the combination including feeding mechanism, controlling mechanism therefor including an elastic feed restraining member, a brake lining disposed between the same and a part of said feeding mechanism, and a resilient container housing said brake lining.
- 35 10. In an apparatus of the character described, the combination including feeding mechanism, controlling mechanism therefor including an elastic feed restraining member, a plural part brake lining disposed between the same and a part of said feeding mechanism, and a resilient container housing said brake lining.
11. In an apparatus of the character described, the combination including feeding mechanism, controlling mechanism therefor including an elastic feed restraining member, a plural part brake lining disposed between the same and a part of said feeding mechanism, and a plural part resilient container housing said brake lining.
12. In an apparatus of the character described, the combination including feeding mechanism, feed controlling mechanism including a spring disposed around one of the elements thereof, a resilient housing means disposed within said spring, and a brake lining disposed within said housing.
13. In an apparatus of the character described, the combination including feeding mechanism, feed controlling mechanism including a coiled spring disposed around one of the elements of the same, a longitudinally slotted housing disposed within said spring, and a brake lining disposed between said housing and said feeding element.
14. In an apparatus of the character described, the combination including feeding mechanism, controlling means therefor including a coiled spring disposed around one of the elements thereof, a two-part resilient housing means disposed within said spring, and a brake lining carried in each of said parts and engageable with said element.
15. In an apparatus of the character described, the combination including feeding mechanism including a reciprocable member, feed controlling mechanism including a coiled spring disposed around said member, a two-part metallic housing having oppositely disposed longitudinal slots in each of its parts, and a brake lining carried by each of said parts and engageable with said reciprocable member.
16. In an apparatus of the character described, the combination including feeding mechanism having a longitudinally movable element, controlling mechanism therefor including an elastic feed restraining member surrounding said element, and a non-rotative braking member disposed between said restraining member and said element.
17. In an apparatus of the character described, the combination including feeding mechanism having a longitudinally movable element, controlling mechanism therefor including an elastic feed restraining member surrounding said element, and a braking member disposed between said restraining member and said element and engageable with the latter.
18. In an apparatus of the character described, the combination including feeding mechanism having a longitudinally movable element, controlling mechanism therefor including an elastic feed restraining member surrounding said element, and a braking member disposed between said restraining member and said element, said braking member having a frictional engagement with said element.
19. In an apparatus of the character described, the combination including feeding mechanism, a head thereon, controlling mechanism therefor including an elastic feed restraining member, and a braking member loosely disposed between said restraining member and a part of said feeding mechanism and adapted to engage said restraining member and part and said head.
20. In an apparatus of the character described, the combination including feeding mechanism, a head thereon, controlling mechanism therefor including an elastic feed restraining member, and a braking member loosely disposed between said restraining member and a part of said feeding mechanism and adapted to engage said restraining member and part and said head to transfer the restraining force of the frictional engagement to said head.

21. In an apparatus of the character described, the combination including feeding mechanism, controlling mechanism therefor including an elastic feed restraining member surrounding a part of said feeding mechanism, a brake lining freely disposed between the restraining member and said

part of said feeding mechanism, and an elastic container housing said brake lining, said brake lining and container being slotted 10 longitudinally alternately on opposite sides.

In testimony whereof I affix my signature.

GEORGE H. GILMAN.
